DUPLEX FEEDING MECHANISM FOR
SEWING MACHINESHenry Feldmann, Brooklyn, N. Y., assignor to
Joseph Galkin Corporation, New York, N. Y.,
a corporation of New York

Application April 11, 1935, Serial No. 15,747

3 Claims. (Cl. 112—214)

This invention relates to feeding mechanism for sewing machines, and particularly to a duplex feeding mechanism having an upper positively rotated feed roller and a lower positively rotated feed roller cooperating therewith by means of intermeshing gears, each of said rollers having intersecting grooves which provide diamond-shaped projections disposed so as to eliminate interengagement thereof.

10 An object of this invention is to provide a simple and efficient duplex and positive feed roller feeding mechanism which shall be adaptable to sewing machines of various types, but particularly adaptable to sewing machines designed for attaching waistbands and belt loops to trousers.

Another object of this invention is to mount the upper feed-roller in a bracket attached to the sewing machine frame for up and down movement independent of the lifter-foot of the 20 sewing machine.

Another object of this invention is to cause pressure against the upper feed-roller by a spring mounted in longitudinal alignment with the feed-roller shaft, the pressure on the roller being independent of the lifter-bar.

With the above and other objects in view, the invention will be hereinafter more particularly described, and the combination and arrangement of parts will be shown in the accompanying drawings and pointed out in the claims which form part of this specification.

Reference will now be had to the drawings, wherein like numerals of reference designate corresponding parts throughout the several views, 35 in which:

Figure 1 is a front view of a sewing machine embodying my duplex roller feeding mechanism.

Figure 2 is an end view, partly in section and showing the manner of mounting the feed rollers.

40 Figure 3 is a fragmentary end view partly in section, the section being taken as on line 3—3 in Figure 1, and shows clutch mechanism for driving the feed roller shafts with a step-by-step or intermittent movement.

45 Figure 4 is a sectional view, the section being taken as on line 4—4 in Figure 1, and shows brake mechanism for preventing reverse movement of the feed roller shafts.

50 In the illustrated embodiment of the invention, the numeral 10 indicates the work supporting base of a sewing machine embodying my invention and which comprises the usual standard 11, having an overhanging arm 12 with a head 13 at its free end. In the head 13 is journaled the

usual reciprocating needle-bar 14 carrying a needle 15. The needle-bar is reciprocated by a lever 16 mounted on a pivot shaft 17. A looptaker 18 is oscillated and cooperates with the needle to form straight line stitching as is well known in the sewing machine art. The material worked upon is held down by a presser foot 19 resting on a cloth plate 20 secured to and above the work supporting base 10.

5 The presser foot 19 is pivotally connected to a presser foot shank 21 by means of a screw 22 and a pressure is maintained upon said foot by means of a coil spring 23 housed in a recess in the upper portion of the shank 21 and which reacts against the upper portion of a presser 15 foot bracket 24. The shank 21 is slidably mounted for extensive vertical motion in the bracket 24. The bracket 24 is mounted in slidable relation to the head 13 of the sewing machine. It is to be noted that the presser foot 19 is designed 20 mainly for vertical sliding motion, the pivotal motion of the presser foot about the screw 22 being limited to very slight rocking motions by pins 30 projecting from the shank 21.

This invention relates particularly to a duplex 25 feeding mechanism comprising a positively driven knurled roller or feed-wheel 25 mounted above the work supporting base 10, and a positively driven knurled roller or feed-wheel 26 mounted below said base and projecting above an aperture 30 formed in the cloth plate 20, each of said rollers having intersecting grooves which provide diamond-shaped projections disposed so as to eliminate interengagement thereof. The upper feed-

35 roller 25 is rotated by a shaft 27. The end of the roller 25 adjacent the needle 15 is rotatably mounted on a stud 28 projecting from the bracket 24. The bracket 24 is fastened to a vertical lifter pin 29 which is slidably mounted for vertical 40 motion in a bearing 31. The bracket 24 is also mounted for vertical sliding motion on a guide bar 32, secured in bearing 33 in the head 13. The lifter pin 29 has a head 34 at its upper end which is elevated to permit a forked arm 35 to 45 engage the head of the lifter pin 29. The forked arm 35 is fixed to a lifter bar 36 which is slidably mounted in bearings in the head 13. The lifter bar may be raised by a lever 37. When the lifter bar 36 is raised, the attached forked arm 35 50

also raises the lifter pin 29, the bracket 24 and the upper feed roller 25. An arcuate leaf spring 38 bears at one end on a spring rest 39 and at the other end on a ball 40 seated in the top face of the bracket 24, and this pressure is trans- 55

mitted to a top support 41 which bears on the hub of the feed roller 25. An adjusting screw 42 threaded in a bracket 43 rests on the spring 38 at about its middle and causes the spring to 5 press on the ball 40 and to force the feed roller 25 yieldingly in a downward direction against the lower feed roller 26. The lower feed roller 26 is rotated by a shaft 44 which is mounted longitudinally of said sewing machine in bearings 45 and 46 attached to the base plate 47 of the sewing machine. Intermeshing gears 48 and 49 mounted on the shafts 27 and 44 connect the rollers 25 and 26 into rotary cooperating relation. Both of the feed rollers have knurled operating faces which engage the fabric to be fed, and enables the rollers to grip a fabric between them and to impart positive feeding movements both from above and below the fabric when the rollers are rotated concomitantly by the gears 48 and 49.

10 The upper feed roller 25 is slidably movable vertically in a straight line with and also independently of the lifter bar 36. The presser foot 15 is also slidably movable vertically in a straight line independent of the vertical motion of the roller 25. These relative vertical sliding motions are of great advantage when the sewing machine is used for attaching looped waistbands to trousers in which operation the presser foot 20 has first to rise to the top of the loop while the roller is in a lower position on the trouser fabric and wherein the roller then rises to the top of the loop while the presser foot is in a lower position.

15 It is desired that a positive rotary step-by-step driving or feeding motion be imparted to the shaft 27, to a universal joint 50, and to the feed rollers 25 and 26 without lost motion, and that a longer or shorter step-by-step or intermittent motion may be had and modified at will 25 within a considerable range of adjustment. For this purpose I employ an oscillatable clutching 30 detent carrier 55 mounted within a casing 56, fixed to the shaft 27, as best shown in Figure 3. A cover plate 51 having an arm 58 has been fastened to the clutching detent carrier 55. The arm 58 is pivotally connected at one end to a link 57, fastened to a crank arm 59 on a rock-shaft 60. The rock-shaft 60 receives its movements from the main actuating shaft 61 of the 35 sewing machine through a series of parts which include an adjustable crank 62 on the end of the main actuating shaft 61, as shown in Figure 2.

40 In order to positively prevent reverse movement of the shafts 27 and 44 without lost motion, I have provided a braking detent carrier 65 mounted within the casing 56, as best 45 shown in Figure 4. A cover plate 66 having an arm 67 has been fastened to the braking detent carrier 65. The arm 67 is secured to the spring rest member 39 which is fastened to the base plate 47 of the sewing machine.

45 The clutch detent carrier 55 and the braking detent carrier 65 are mounted on the shaft 27 to work in opposite directions and may be in the form shown and described in Patent No. 1,985,406, issued to Nathan B. Galkin, dated December 25, 1934. By actuating a screw 69, Figure 2, the crank 62 is caused to move to or away from the center of the shaft 61 and causes a link 70 to 50 impart a larger or smaller swing to the rock shaft 60, to the arm 59, to the link 57 and to the clutch arm 58. The clutch arm 58 is secured to the cover plate 51 and to the clutch detent carrier 55. 55 The swing of the arm 58 imparts an intermittent

5 tent rotation to the casing 56 and through a screw 68 to the shafts 27 and 44. The screw 69 thus serves to modify the feeding movements imparted to the feeding rollers 25 and 26. The braking detent carrier being fixed to the sewing machine frame, causes the shaft 27 to be gripped at the end of each feeding movement without any lost motion or back-lash at the feed rollers. The hub of the feed roller 25 and the shaft 27 may be coupled by means of a universal joint 50 so that power imparted to the shaft 27 will be transmitted to the roller 25 whatever operative position said roller may occupy.

10 As best shown in Figure 4, the spring 38 is mounted in central alignment with the axis of 15 the shaft 27 and the roller 25 and this axial alignment insures ease of vertical sliding motion necessary for quickly repeated reciprocations incident to high speed sewing machine operation.

I claim:

1. A two-roller feed mechanism for sewing machines having a head, said feed mechanism being designed to independently and concomitantly grip and feed superposed layers of fabric having widely spaced upper and lower surfaces, said feed mechanism comprising an upper positively driven feed roller rotatably mounted horizontally and being movable in a vertical plane, a lower positively driven feed roller rotatably mounted horizontally and rotated concomitantly with said upper roller by means of intermeshing gears, each of said rollers having intersecting grooves which provide diamond-shaped projections disposed so as to eliminate interengagement thereof, a presser foot yieldingly pressing on the material being stitched, said feeding mechanism being located in the rear of said presser foot, means for supporting a carrier on which said upper feed roller and said foot are separately mounted for independent vertical sliding motion relative to each other and relative to said head, an elongated leaf-spring positioned in alignment with said upper feed roller axis for yieldingly depressing said carrier, roller detent clutch means for imparting step-by-step rotary movements to said feed rollers in one direction and roller detent clutch means for preventing reverse movement of said feed rollers.

2. A two-roller feed mechanism for sewing machines having a head, said feed mechanism being designed to independently and concomitantly grip and feed superposed layers of fabric having widely spaced upper and lower surfaces, said feed mechanism comprising an upper positively driven feed roller rotatably mounted horizontally and being movable in a vertical plane, a lower positively driven feed roller rotatably mounted horizontally and rotated concomitantly with said upper roller, each of said rollers having intersecting grooves which provide diamond-shaped projections disposed so as to eliminate interengagement thereof, a presser foot yieldingly pressing on the material being stitched, said feeding mechanism being located in the rear of said presser foot, means for supporting a carrier on which said upper feed roller and said foot are separately mounted for independent vertical sliding motion relative to each other and relative to said head, a spring for yieldingly depressing said carrier, clutch means for imparting step-by-step rotary movements to said feed rollers in one direction and clutch means for preventing reverse movement of said feed rollers.

3. A two-roller feed mechanism for sewing machines designed to independently and concomitantly grip and feed superposed layers of fabric

having widely spaced upper and lower surfaces, comprising an upper positively driven feed roller rotatably mounted horizontally and being movable in a vertical plane, a lower positively driven feed roller rotatably mounted horizontally and rotated concomitantly with said upper roller, a presser foot yieldingly pressing on the material being stitched, said feeding mechanism being located in the rear of said presser foot, said upper feed roller and said foot being separately mounted for independent vertical sliding motion, said presser foot being movable vertically without affecting the vertical position or the rotation of said upper feed roller, means for yieldingly depressing said upper roller, means for imparting step-by-step rotary movements to said feed rollers in one direction and means for preventing reverse movement of said feed rollers, said lower roller being mounted at one end of a shaft positioned below the work supporting base of the sewing machine, said shaft extending longitudinally of said machine and having a gear mounted at its other end for driving said lower roller, said feed mechanism being designed to permit insertion of fabric intermediate said rollers with the edges thereof disposed beyond the ends of the rollers. 5 10

HENRY FELDMANN.
